CLAIM

The ornamental design for a pouch, as shown and described.

DESCRIPTION

FIG. 1 is a top prospective view of a pouch showing my new design;

FIG. 2 is an enlarged front elevation, the rear being identical;

FIG. 3 is an enlarged side elevation of FIG. 2, the opposite side being identical;

FIG. 4 is an enlarged top view of FIG. 2;

FIG. 5 is an enlarged bottom view of FIG. 2;

FIG. 6 is a top perspective view of a second embodiment of FIG. 1, the difference being the addition of a closure strip;

FIG. 7 is an enlarged front elevation of FIG. 6;

FIG. 8 is an enlarged rear elevation of FIG. 6;

FIG. 9 is an enlarged side elevation of FIG. 6, the opposite side being a mirror image;

FIG. 10 is an enlarged top view of FIG. 6;

FIG. 11 is an enlarged bottom view of FIG. 6;

FIG. 12 is a top perspective view of FIG. 6 in a closed position.
